UNITED STATES PATENT OFFICE.

CLARENCE R. WELCH, OF SCRANTON, PENNSYLVANIA.

CONTROLLING APPARATUS FOR HOISTING-ENGINES.

1,108,044.

Specification of Letters Patent. Patented Aug. 18, 1914.

Application filed May 1, 1912. Serial No. 694,564.

To all whom it may concern:

Be it known that I, CLARENCE R. WELCH, a citizen of the United States, residing at Scranton, in the county of Lackawanna and State of Pennsylvania, have invented new and useful Improvements in Controlling Apparatus for Hoisting-Engines, of which the following is a specification.

This invention has reference to controlling apparatus for hoisting engines, and more especially to controlling apparatus of the general type shown and described in my prior Patent, No. 965779, granted July 26, 1910.

It comprehends, primarily, certain improvements in or relating to the trip device and the operating mechanism associated therewith, as hereinafter described, the construction and arrangement of the component parts of the apparatus being such as to insure an automatic setting of the brakes under predetermined conditions.

A structural embodiment of the invention is illustrated in the accompanying drawings, wherein—

Figure 1 is a side elevation of the complete apparatus, showing the parts in normal position; Fig. 2 is a similar view, with the parts in tripped position; Figs. 3 and 4 are, respectively, a horizontal section on the line 3—3, and a vertical section on the line 4—4 of Fig. 2; and Fig. 5 is a fragmental perspective view of the trip device and its operating mechanism.

In said drawings, A indicates, in a general manner, the engine controller, B the governor, C the trip, and D the trip-operating mechanism.

The controller A consists, in the present instance, of a cylinder 1 in which is movable a piston 2 whose stem is connected to the brake-operating lever 3, the movement of the piston requisite to set the brakes being effected either by the manual actuation of said lever or by the entrance of a motive fluid through the pipe line 4 into cylinder 1. The passage of the fluid through the pipe line 4 is regulated by means of a throttle valve 5 located in that section of said line which is directly adjacent the trip and its operating mechanism. Upon this section there is mounted an upstanding arm 6 to whose upper end is pivoted the forked end of a bar 7 which, intermediate its ends, carries a threaded pin 8, or the like, designed to engage and depress the stem of valve 5,

when bar 7 is depressed, so as to close said valve. The valve may be equipped with a suitable controlling spring, (not shown), by means whereof it is normally held in raised 60 or open position.

The valve operating bar 7 is held in depressed position by the trip C, which latter, in the construction illustrated, comprises a rocking upstanding arm 9 pivoted at its 65 lower end to a collar 10 mounted on the pipe line at the opposite side of valve 5 from arm 6. The upper end of the trip arm is provided with a laterally projecting finger 11 which is designed to engage the outer end 70 of bar 7, said bar being provided, in turn, at the point indicated, with a finger or shoulder 12 that extends toward the trip and is, or may be, produced by cutting away a portion of the bar, as shown in Fig. 5. 75

To operate the trip, the mechanism D is provided, this mechanism including primary and secondary actuating members 13 and 14, and 15 and 16, respectively, a traveling member 17 for co-action with said 80 actuating members, and a pair of shafts 18 and 19 whereon all of said members are mounted. Said shafts are disposed horizontally and supported in spaced parallel relation in the end pieces of a frame 20 85 which is supported, in turn, upon an upright 21 that is located beneath and directly adjacent the controlling valve and the trip. Shaft 19 is threaded, as shown, and carries the traveling member 17, here depicted as 90

in the form of a sleeve nut; it is driven from the main shaft 23 of the engine through the agency of intermeshing gears 24 and 25, or in any other suitable manner, and is operatively connected with the governor B, whose shaft 26 carries a gear 27 in mesh with gear 25 and is, itself, journaled in a bracket 28 projecting upwardly from and secured to frame 20. The gears 24, 25 and 27 bear such a predetermined ratio to 95 each other, and the length of shaft 19 is so proportioned that the time consumed by the travel of nut 17 from one end of the threaded portion of said shaft 19 to the other is directly proportional to that of the cage 100 (not shown) in the elevator shaft. Shaft 18 is designed for endwise movement in its bearings in frame 20, and, also, for a slight rocking movement under the conditions hereinafter set forth, these movements being caused by the co-action of nut 17 with any one of the members 13 and 14, or 15 105 110

and 16, and the actuation of the governor. The two primary members 13 and 14 are preferably constituted by collars which are provided with noses 29 and 30 that extend transversely of the frame toward and beneath shaft 19 and below the path of movement of nut 17, while the secondary members 15 and 16 are formed by similar collars whose noses 31 and 32 project, however, directly toward said shaft into the path of movement of said nut. The several collars are adjustable longitudinally of shaft 18 and are held in adjusted position thereon by means of set-screws 33 or other suitable retaining devices. The aforementioned arrangement is such, therefore, as to insure an endwise movement of shaft 18 when nut 17 strikes against any one of the said collars, but, under normal conditions, said nut will contact only with the secondary collars 15 and 16, which are disposed adjacent the ends of said shaft, and will pass freely over the noses of the intermediate primary collars. In other words, when the cage, (and, hence, the threaded shaft 19), is moving at a normal rate of speed, the primary collars will be inoperative, and no endwise movement of shaft 18 will take place until the nut strikes against the nose of either of the secondary collars, which occurs shortly before the cage reaches one end or the other of the elevator shaft.

In order to produce the rocking movement of shaft 18 requisite to bring the noses on the primary collars into operative position, a connection between said shaft and the governor is provided, whereby the actuation of the latter will automatically effect such movement. To this end, there is included in or operatively associated with the governor a bell-crank lever 34 which is fulcrumed at its apex at the extremity of a second bracket 35 secured to frame 20, in which bracket the tubular stem 36 of the governor is journaled. The long horizontal arm of said lever carries an adjustable weight 37 and is connected at its free end by a link 38 to a crank arm 39 secured to the adjacent end of shaft 18, while the short vertical arm of the lever has a loose pivotal connection at its free end with a sleeve 40 secured to the adjacent end of an endwise-movable rod 41 slidably fitted in stem 36, the rear end of said rod terminating in a head 42 that bears against the in-turned arms of the governor levers 43. In consequence, when the speed at which the engine is running becomes excessive, the outward movement of the governor levers will occasion an outward endwise-movement of rod 41, (toward the left, with respect to Fig. 1), which will produce, in turn, an upward rocking movement of lever 34, with the result that link 38 will be pulled upwardly and thereby rock shaft 18

in the desired manner, by reason of its connection with crank 39. Collars 13 and 14 will be rocked with said shaft, as is apparent, and their noses thus brought into position to be struck by nut 17 according to the direction in which the latter is moving. To prevent said nut from rotating with shaft 19, it is provided with a rearwardly-extending key 44 which projects into a longitudinal groove 45 formed in the inner face of the rear piece or member of frame 20.

The endwise movements of shaft 18 are transmitted to the trip, in order to operate the same by means of a grooved collar 46 which is suitably fastened to said shaft, the groove therein receiving the free end of a rearwardly-extending pin 47 secured to arm 9. In consequence, when nut 17 strikes against the nose of any one of the collars 13, 14, 15 or 16, on shaft 18, said shaft will be shifted in one direction or the other, and its grooved collar will rock the trip arm in the same direction, thus releasing finger 11 from the shoulder 12 on bar 7, whereupon valve 5 will be free to open automatically under the influence of its controlling spring.

The invention, and its mode of operation as a whole, are believed to be apparent from the foregoing, and to require no further description.

I claim as my invention:

1. In an engine controlling apparatus, the combination of a trip; a movable element permanently connected with said trip for operating the same; primary and secondary actuating means carried by said element; and a member arranged to engage either said primary or said secondary actuating means under predetermined conditions, to move said element.

2. In an engine controlling apparatus, the combination of a trip; a movable operating element therefor; normally inoperative primary actuating means and normally operative secondary actuating means carried by said element; means for moving said element in one direction, to bring said primary actuating means into operative position; and a member arranged to engage either said primary or said secondary means under predetermined conditions, to move said element endwise.

3. In an engine controlling apparatus, the combination of a trip; a movable operating element therefor; normally inoperative primary actuating means and normally operative secondary actuating means carried by said element; means for rocking said element about its longitudinal axis, to bring said primary actuating means into operative position; and a member arranged to engage either said primary or said secondary means under predetermined conditions, to move said element endwise.

4. In an engine controlling apparatus, the combination of a trip; a movable operating element therefor; normally inoperative primary actuating means and normally operative secondary actuating means carried by said element; governor-controlled means for rocking said element to bring said primary actuating member into operative position; and a member arranged to engage either said primary or said secondary actuating means under predetermined conditions, to move said element.

5. In an engine controlling apparatus, the combination of a trip; an endwise-shiftable element connected therewith; a traveling member movable with relation to said element; a collar carried by said element and provided with a nose adapted for movement into and out of position in the path of said member, said member being adapted to engage said nose when the latter occupies the first-named position; means for rocking said element, to bring said nose into such position; and means for operating said member.

6. In an engine controlling apparatus, the combination of a trip; an endwise shiftable element associated with said trip for operating the same; a traveling member movable with relation to said element; a collar carried by said element and provided with a nose adapted for movement into and out of position in the path of said member, said member being adapted to strike said nose when the latter occupies the first-named position to shift said element endwise and actuate said trip; governor-controlled means connected with said element for rocking the same in one direction, to bring said nose into such position; and means for operating said member.

7. In an engine controlling apparatus, the combination of a trip; an endwise shiftable element associated with said trip for operating the same; a traveling member movable with relation to said element; a pair of collars carried by said element and provided, each, with a nose against either of which said member is adapted to strike under predetermined conditions during its movement to shift said element endwise and operate said trip, the nose on one collar being normally disposed out of and the nose on the other collar normally in the path of movement of said member; means for rocking said element to bring the nose on the first-named collar into said path; and means for operating said member.

8. In an engine controlling apparatus, the combination of a trip; a pair of parallel

shafts, one of which is threaded; a member secured to the other shaft and connected directly to said trip; means for rotating the first-named shaft; a collar traveling on said first-named shaft during the rotation thereof; and primary and secondary actuating means secured to the second-named shaft, either of said actuating means being adapted to be struck by said collar under predetermined conditions, to shift said second-named shaft endwise and operate said trip.

9. In an engine controlling apparatus, the combination of a trip; a pair of parallel shafts, one of which is threaded; a member secured to the other shaft and connected directly to said trip; means for rotating the first-named shaft; a collar traveling on said first-named shaft during the rotation thereof; normally inoperative primary actuating means and normally operative secondary actuating means secured to the second-named shaft; and means for rocking said second-named shaft, to bring the primary actuating means into operative position, either of said actuating means being adapted to be struck by said collar under predetermined conditions, to shift said second-named shaft endwise and operate said trip.

10. In an engine controlling apparatus, the combination of a trip embodying a rocking arm provided with a pin, and a cooperative part adapted to be engaged and released by said arm; an endwise-movable trip-operating element provided with a collar having a circumferential groove wherein said pin is engaged, for rocking said arm, to release said part, when said element is moved endwise; and means for moving said element endwise.

11. In an engine controlling apparatus, the combination of a trip embodying a rocking arm provided with a pin and a part cooperative with said arm; a movable element for operating said trip provided with a collar having a circumferential groove wherein said pin is engaged; a normally inoperative actuating member carried by said element; means for rocking said element about its longitudinal axis, to bring said actuating member into operative position; and a member adapted to engage said actuating member, for moving said element endwise.

In testimony whereof I have hereunto set my hand in presence of two subscribing witnesses.

CLARENCE R. WELCH.
